UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

TELEGRAPHY.

No. 888,510.

Specification of Letters Patent.

Patented May 26, 1908.

Application filed August 9, 1906. Serial No. 329,882.

To all whom it may concern:

Be it known that I, ISIDOR KITSEE, citizen of the United States, residing at Philadelphia, in the county of Philadelphia and 5 State of Pennsylvania, have invented certain new and useful Improvements in Telegraphy, of which the following is a specification.

My invention relates to an improvement 10 in telegraphy and has more special reference to telegraphy wherein true reversals are employed, that is, wherein an impulse of one polarity always follows an impulse of opposite polarity and all the impulses are of equal 15 strength and duration. In such system, especially if the line is of comparatively large resistance and capacity, instruments have to be employed very delicate in their construction. It was found that where the impulses 20 are feeble and of short duration, they cannot well operate a sensitive instrument, so as to make a good contact, but they can operate the same, so as to break a normally made contact. In such system, it is necessary to 25 provide means, so that the translating instrument, if the same consists of an electro-magnet, such as a sounder, is operated in accordance with the characters transmitted.

In the drawing, 1 and 2 are the line of 30 transmission; 3, the receiving device inserted in said line. This receiving device is provided with the armature 4 normally resting against the contact 5. The armature is connected through wire 6 with battery 8 and the 35 contact 5 through wire 23 with one terminal of the electro-magnet 10. The battery 8 is connected through wire 9 with the other terminal of said electro-magnet. This electro-magnet is provided with the armature 11 adapted to operate the escapement 12 and this escapement is in operative relation to the star-wheel 13. 15 is a source of power, here shown as a motor, on the shaft of the armature of which are mounted the commutator 14 and the star-wheel aforesaid. The 40 commutator has conducting bars alternating with non-conducting spaces. The brushes 16 and 17 in operative relation to the commutator are connected through wires 18 and 19 and battery 20 with the translating device 22. At the transmitting station is the 45 transmitting device, here comprising the batteries 24 and 25 and the transmitting key 26.

As long as the lever of the key is not de-

pressed, the shunt around battery 24 is not made and as the battery 24 consists of a greater number of cells than 25, a current will flow over the line in the direction of the unfeathered arrow, but when the key is depressed, the battery 24 is shunted and the battery 25 comes into play and a current will flow over the line in the direction of the feathered arrow. If the line is of a great capacity and it is desired to limit the flow of the current, a condenser should be placed in the line, preferably between the two sources of current 24 and 25.

The operation of this device is as follows: It is supposed that the line has a great capacity and that it is desired to transmit true reversals, that is, alternating impulses always of the same duration and intensity and that, therefore, a condenser 21 is placed in the line. Normally, therefore, no current 70 will pass over the line and the armature 4 will rest against its stopping point 5. When the operator desires to transmit a message, he depresses the key, with the result that an impulse in the direction of the feathered 75 arrow, will flow over the line. It is assumed, that normally, the brushes 16 and 17 rest on an insulating space of the commutator 14. Through the flow of this impulse, the electro-magnet 3 will be energized, the armature 80 4 will be drawn away from the stop 5, but will, as the impulse is only a momentary one, fall back again to its stop. But during the time that the armature has left the stop, the circuit of the electro-magnet 10 is broken 85 90 the armature which was formerly drawn towards the cores, will now fall back and the star-wheel 13 will be actuated, thereby allowing the commutator to move a distance equal to one of the teeth, and as the commutator is so arranged that for each second tooth, a conducting bar is presented to the brushes 16 and 17, it is obvious that these brushes, which formerly rested on the insulating part, will now come to rest on the 95 100 conducting part of this commutator. They will, therefore, close the circuit containing the translating device 22 and the same will be actuated. As long as the transmitting operator holds the key depressed, no other 105 impulse will flow over the line, but when the lever of the key is released, the shunt around the source 24 is opened and an impulse will flow over the line in the direction of the unfeathered arrow. This impulse will again 110

actuate the device 3, the armature 4 will again be momentarily drawn away from 5, the circuit will again be broken and as a result thereof, the escapement 12 and thereby the star-wheel 13 will be actuated. This will move the commutator a space sufficient to move the brushes 16 and 17 from the conducting bar and place the same in contact with the insulating part. The circuit of 22 5 will thereby be broken and the electro-magnet therein be deenergized. It is supposed that 22 represents one of the well-known telegraphic sounders. As long as the circuit for this sounder is made, the armature will be drawn downwards and will produce the so-called downstroke and when the circuit is broken, the armature will be drawn upwards by its spring and will produce the so-called upper stroke; and as the closing 10 time of this circuit coincides with the depression of the key and the opening time of this circuit with the time-unit the key is not depressed; it is obvious that the sounder 22 will answer to the transmission in the same manner as the sounder answers in the telegraphic systems of to-day.

Having now described my invention, what I claim as new and desire to secure by Letters Patent is:

30 1. In a telegraphic system means to transmit reversals, a receiving device inserted in the line, a local translating device, and localized commutating device operatively related to said receiving device to make operative 35 said translating device through one of the impulses received and make inoperative said translating device through the second of said impulses received.

2. A telegraphic system comprising transmitting stations and receiving station, the transmitting stations embracing means to transmit reversals, the receiving stations embracing an electro-magnetic receiver, the armature normally in contact with a con-

ductor, a local circuit for armature and conductor, embracing source of current and a commutating device, in combination with a translating device operated by said commutator, a circuit for same, and contacting means for said circuit.

3. In a system of telegraphy means to transmit impulses, means to receive the same and translate the same into readable characters, said means comprising an electro-magnet inserted in the line of transmission, a local circuit therefor, a commutator, electro-magnetic means to actuate said commutator, a translating device and means whereby through the movement of said commutator a circuit for said translating device is alternately made and broken.

4. In telegraphy, a receiving and translating device comprising the electro-magnetic receiver proper, a commutating device, electro-magnetic means to operate the same, a translating device and means to close the circuit for said translating device through each alternate action of said commutating device, the actuating means in operative relation to the receiver proper.

5. In telegraphy, means to receive and translate transmitted impulses, the first means comprising an electro-magnet, the coil therefor connected in the line, a movable armature and stationary contact for 75 said electro-magnet, both normally in contact with each other, an electric circuit therefor, a commutating device in operative relation to said electric circuit, a translating device, an electric circuit therefor, and 80 means to operate said circuit through said commutating device.

In testimony whereof I affix my signature in presence of two witnesses.

ISIDOR KITSEE.
